RADIATOR CAP

Moses E. Cheney, Toledo, Ohio, assignor to Moto
Meter Gauge & Equipment Corporation,
Toledo, Ohio, a Corporation of Delaware

Application January 16, 1931. Serial No. 509,244

5 Claims. (Cl. 220—40)

My invention consists of a simple and economical construction of cap for the radiators of automobiles, a cap which can be applied and detached easily but which will hold firmly in place 5 when applied.

In the accompanying drawing—

Figure 1 is a side elevation of the cap;

Fig. 2 a vertical section, and

Fig. 3 an inverted plan view.

10 My improved cap is of the bayonet joint fastening type, that is to say, the cap is provided on its underside with radially projecting fingers which enter and engage in bayonet grooves in the inside of the filling neck of the radiator of the automobile. In Fig. 2, this radiator neck is indicated 15 in dotted lines at 10.

The cap A is preferably provided on its underside within its peripheral flange *a* with a gasket B, which will come to rest upon the top of the filling neck 10. The radial fingers *f*—*f*, which are carried by the cap to engage the bayonet grooves in the neck of the radiator are formed on a sheet metal cup-piece F.

As shown in Figures 1, 2 and 3, the fingers *f*—*f* 25 are preferably integral with the sheet metal cup-piece F, being channel shaped in cross-section with depending flanges which are carried around the cup-piece. This cup-piece is normally held up to the underside of the cap A by means of a helical spring S carried by a centre piece T in 30 the form of a hollow thimble with an annular flange *t* at the bottom, on which the lower part of the helical spring S is supported while the upper end of the spring bears against the underside of the cup piece F.

The thimble T is of material diameter, so as 35 to be close to the inner periphery of the spring S. This thimble is secured to the underside of the cap A by a screw C passed through the hollow thimble and threaded into the underside of the cap, the large head of the screw lying inside the thimble.

The cup piece F is prevented from turning 40 about the centre piece by reason of the fact that teats *g* (three in the present instance) cast or otherwise formed on the underside of the cap pass through corresponding openings in the cup-piece F.

50 I claim:

1. A radiator cap, provided with a movable cup-piece having radial fingers in combination with a flanged hollow thimble and securing means having a head in the hollow of said thimble and 55 securing it to the underside of the cap and a

helical spring supporting the cup-piece on the flanged thimble.

2. A radiator cap, provided with a movable cup-piece having radial fingers with a depending flange extending onto said cup-piece, in combination with a flanged hollow thimble and a screw 60 securing it to the underside of the cap, and a helical spring supporting the cup-piece on the flanged thimble.

3. A radiator cap, provided with a movable cup-piece having radial fingers, in combination with a flanged hollow thimble and a screw securing it to the underside of the cap, the head 65 of said screw lying within said thimble and a helical spring supporting the cup-piece on the flanged thimble.

4. A radiator cap, provided with a movable sheet metal cup-piece having radially projecting fingers formed thereon, in combination with a hollow thimble having an annular flange at the 75 bottom, means for securing the top of said thimble to the underside of said cap, and resilient means bearing on said annular flange and engaging the underside of said cup-piece for yieldably holding the same up against the underside 80 of said cap.

5. A radiator cap of the bayonet joint fastening type provided on its underside with a sheet metal cup-piece having radially projecting fingers formed thereon which enter and engage in bayonet grooves in the inside of the filling neck, in combination with a hollow thimble having an 85 annular flange at the bottom, a screw passed therethrough and threaded in the underside of the cap to secure said thimble thereto, and a helical spring carried by said thimble and bearing on said annular flange for holding up said 90 sheet metal cup-piece.

MOSES E. CHENEY.
